UNITED STATES PATENT OFFICE.

WALDEMAR H. SPANIER, OF DEVILS LAKE, NORTH DAKOTA.

WRENCH.

1,349,631.

Specification of Letters Patent. Patented Aug. 17, 1920.

Application filed January 28, 1920. Serial No. 354,685.

To all whom it may concern:

Be it known that I, WALDEMAR H. SPANIER, a citizen of the United States, residing at Devils Lake, in the county of Ramsey 5 and State of North Dakota, have invented a new and useful Wrench, of which the following is a specification.

This invention relates to wrenches, and particularly to that class having twin jaws 10 pivotally mounted in opposed relation to each other in a relatively stationary body member, said jaws proper comprising the short ends of levers which are adapted to be forced together to give a powerful 15 gripping action, through the medium of a pivoted actuating handle located between the said levers and having alternate engagement with the long ends of the levers to actuate one or the other thereof, depending 20 upon the direction of rotation of the wrench.

The object of the invention is to provide a wrench of this character wherein the functions are performed by a minimum 25 number of parts, which are formed in a simple manner, and to so proportion the same as to secure the greatest amount of leverage, thus providing a wrench having the maximum power.

30 A full and complete understanding of the invention may be obtained from a consideration of the following detailed description, taken in connection with the accompanying drawing forming a part of this 35 specification, it being understood that while the drawing shows a practical form of the invention, the latter is not confined to strict conformity therewith, but may be changed and modified, so long as such changes or 40 modifications mark no material departure from the salient features thereof, as specifically pointed out in the appended claims.

In the drawing, in which similar reference characters designate corresponding 45 parts throughout the several figures,

Figure 1 is a top plan view of a wrench constructed in accordance with the present invention;

Fig. 2 is a side view of the same;

50 Fig. 3 is a horizontal sectional view thereof.

The wrench comprises an elongated body member composed of a base plate 1 formed of suitable sheet metal, preferably steel, of 55 sufficient thickness to withstand the exces-

sive strain to which such tools are subjected, said base plate having, adjacent to its forward end, a pair of spaced perforations 2, arranged equi-distant from the median line of the base plate, and each perforation being also equi-distant from the front end and the side edges of the plate, the corners of the latter being rounded as at 3, such curvature being struck on the centers of the perforations as an axis. 60

The side edges of the base plate 1 are slightly converged toward the rear end of the latter, which has its rear corners cut away to form inclined walls 4, as clearly illustrated in Fig. 3 of the drawing, and a 70 third perforation 5 is provided through the plate on the median line thereof and midway between the perforations 2 and the rear end thereof.

A pair of identical jaw members 6, preferably formed of hardened steel, are adapted to be mounted on the base plate 1 in straddling relation to the same in the following manner. Each jaw comprises an elongated shank portion 7 having a longitudinal slot 8 formed therein, said slot extending throughout the major portion of the shank 7, and having its forward end wall 9 rounded to correspond to the rounded shoulders 3 of the base plate 1, 80 and its rear end wall 10 inclined to correspond with the walls 4 of the same, the said slot being of a width to snugly receive the base plate and to lie thereon, with the side edges of the base plate flush with the 85 outer edges of the said jaw members.

Adjacent to their forward ends each jaw member is provided with a pair of inwardly extending ears 11, adapted to lie flat against the side faces of the base plate 85 and having centrally disposed perforations in alinement with the respective perforations 2 of the latter, and adapted to be pivotally connected to the same through the medium of rivets 12 traversing the several 100 alined perforations and headed over in the usual manner to prevent their displacement therefrom.

That portion of each jaw member 6 extending forwardly from the front end of 105 the base plate 1 constitutes the jaw proper 13 or active end of the same, and may be straight as shown, or may be curved, or fluted, or toothed as desired, it being customary to curve and tooth said jaws where en- 110

gaging the work, if the device is to be constructed as a pipe wrench, or to leave the same straight for general use, such as for removing or tightening nuts, etc. It will be noted that when the jaws are in their wide open position, as illustrated in Fig. 1 of the drawing, with their outer edges in alinement with the outer edges of the base plate, the working faces of said jaws flare outwardly so as to provide for the ready application of the wrench to the work to be operated upon.

At their rear ends the shanks 7, beyond the inclined terminal walls 10 of the slots 8, are rounded as at 14 and are each provided with a centrally disposed, inwardly directed lug 15, said lug being equal in thickness to the width of the slot 8 and adapted to normally lie flat against the rearmost portions of the inclined walls 4 of the base plate, and in close proximity to the rear end of the latter.

An actuating handle comprising a pair of elongated metallic plates or bars 16 are arranged, one at either side of the base plate, and have their adjacent forward ends rounded as at 17 and provided, centrally of such rounded ends with alined perforations for the reception of a rivet 18, which also traverses the perforation 5 of the base plate, and thus pivotally connects the handle to the base plate and causes the same to act as a lever of the second class in coacting with and actuating the jaws, to cause the latter to act as levers of the first class for exerting a powerful pressure upon the object to be turned.

The handle plates or bars 16 are of a width to fit between the inner opposed edges 40 of the jaw members 6 which normally lie parallel, as in Fig. 1, and the lugs 15 are adapted to fit between the said plates 16 when the jaws are open, and the handle lies in longitudinal alinement with the median 45 line of the base plate, the outer ends of the said plates 16 being held in the corresponding spaced relation by a spacing block 19 which is secured in position, at the ends of the said plates, by suitable rivets 20, the 50 terminals of the plates being rounded so as to obviate any square corners or projecting parts to injure the hands of the operator.

The front ends of the jaws 13 are rounded, as at 21, so as to facilitate the introduction of the said jaws to the work in hand, and to also enable the operator to work in narrow or restricted places, as will be readily understood.

It will be noted that when the handle is 60 in alinement with the center line of the base member, the jaws have their rear lugs 15 located between the plates 16, the shoulders 15^a are located at either side of the said lug and rest upon the opposite edges of the said 65 plates 16, the outer side edges of the jaws

and base member are flush with each other, and the active ends of said jaws are in their wide-open positions for the reception of the maximum size pipe, nut or other object. By moving the handle in either direction, 70 one or the other of the jaws is caused to rock about its pivot 12, by reason of the shoulders 15^a resting upon the edges of the handle plates, the actuating jaw acting as a first-class lever to move the active end of 75 the same into powerful gripping action against the work, the other jaw remaining in its straddling relation to the base plate and forming an immovable abutment to the work, in opposition to the gripping jaw. 80 By reason of the interlocking engagement of the lugs 15 between the plates of the handle, and the fact that the jaws straddle the base plate, the strength of the jaws is materially increased and is positively prevented from 85 any lateral movement, as the lug of the moving jaw rides up the slot between the handle plates as clearly shown in Fig. 3 of the drawing.

From the foregoing it will be seen that a 90 simple, powerful and efficient wrench has been provided which may be manufactured at a low cost, that the same is easily operated, requiring no adjustment and may be adapted for use as a pipe wrench or other 95 uses.

What is claimed is:

1. A wrench comprising a single base plate, a pair of substantially identical jaws pivotally mounted on the opposite side 100 edges of the base plate in opposed relation to each other and arranged longitudinally thereof, the pivots of said jaws being located at the forward end of said plate, and said jaws having their active ends projecting beyond said plate, the rear ends of said jaws normally surrounding the rear end of the plate and having inwardly directed lugs in spaced relation, an actuating hand lever longitudinally slotted so as to lie flat against 105 the opposite sides of the base plate, said slot forming a guideway for said lugs, said lever being fulcrumed at its forward end along the median line of the base plate between the jaws and adapted to contact with the 110 rear ends of the jaws to force the active end of one of the jaws toward the other; one of the said lugs riding in the slot of the hand lever when that jaw is actuated by the same.

2. A wrench comprising a single elongated base plate, a pair of substantially identical jaws slotted longitudinally of their lengths to receive the side edge portions of the base plate, and having inwardly directed perforated ears near their forward active 125 ends, pivots fulcruming the said jaws through the ears to the forward end of the base plate in opposed relation to each other, the active ends of the jaws extending beyond said base plate and the rear ends there- 130

of normally fitting around the rear end of the plate and having centrally disposed lugs directed toward each other, and an actuating hand lever comprising a pair of spaced bars fulcrumed at their forward ends to opposite sides of the base plate at an intermediate point along its median line and joined at their outer ends, the space between said bars forming a slot adapted to receive said lugs when the handle is swung to actuate

one or the other of said jaws by contacting with the rear end thereof.

In testimony that I claim the foregoing as my own, I have hereto affixed my signature in the presence of two witnesses.

WALDEMAR H. SPANIER.
